UNITED STATES PATENT OFFICE

ALBERT E. GUNDELACH, OF CHICAGO, ILLINOIS

DESIGN FOR A COMBINED COASTER AND ASH TRAY

Application filed March 31, 1933. Serial No. 47,656. Term of patent 7 years.

To all whom it may concern:

Be it known that I, ALBERT E. GUNDELACH, a citizen of the United States, residing at Chicago, in the county of Cook and State of Illinois, have invented a new, original, and ornamental Design for a Combined Coaster and Ash Tray, of which the following is a specification, reference being had to the accompanying drawing forming a part thereof.

Figure 1 of the drawing is a plan view of a combined coaster and ash tray embodying the new design; and

Figures 2 and 3 are side and perspective views respectively.

I claim:

The ornamental design for a combined coaster and ash tray, substantially as shown. Chicago, Illinois, March 7, 1933.

ALBERT E. GUNDELACH.
